UNITED STATES PATENT OFFICE

FERDINAND DAVIS, OF UNIONTOWN, PENNSYLVANIA.

SAFETY DEVICE FOR MINE-CARS.

1,132,914.

Specification of Letters Patent.

Patented Mar. 23, 1915.

Application filed March 23, 1914. Serial No. 827,865.

To all whom it may concern:

Be it known that I, FERDINAND DAVIS, a citizen of the United States of America, residing at Uniontown, in the county of Fayette and State of Pennsylvania, have invented certain new and useful Improvements in Safety Devices for Mine-Cars, of which the following is a specification, reference being had therein to the accompanying drawing.

This invention relates to safety devices for mine cars and has for its object to provide means, in a manner as hereinafter set forth, to be operated on a hoisting cage, for controlling the loading of the mine cars upon the cage.

A further object of the invention is to provide a safety device for mine cars, having associated therewith means to permit of the operation of the hoisting cage independently of the loading of the mine cars thereon.

A further object of the invention is to provide a safety device for controlling the loading of mine cars upon a hoisting cage, and operated on the descent of the cage, to release the car whereby the same can be loaded upon the cage, and to lock the car in the rear of the cars released, so that the said rear car will not interfere with that car which is loaded upon the cage.

Further objects of the invention are to provide a safety device for the purpose set forth which is simple in its construction and arrangement, strong, durable, efficient and convenient in its use, readily set up, and comparatively inexpensive.

With the foregoing and other objects in view, the invention consists of the novel construction, combination and arrangement of parts as hereinafter more fully described and illustrated in the accompanying drawings, wherein is shown an embodiment of the invention, but it is to be understood that changes, variations and modifications can be resorted to which come within the scope of the claim hereunto appended.

In the drawings wherein like reference characters denote corresponding parts throughout the several views:—Figure 1 is a top plan view of a safety device in accordance with this invention; Fig. 2 is a transverse sectional view; Fig. 3 is a side elevation; Fig. 4 is a longitudinal sectional view.

Referring to the drawings in detail, 5 de-

notes the bottom of a shaft, for hoisting cage not shown, and at one side of the shaft 5, is a pit 6, the latter being offset at one side as at 7. Arranged within the pit 6 are longitudinally extending parallel supports 8—9, and the latter, in connection with the walls 10—11 of the offset portion 7, provide a pocket upon the bottom of which is arranged a base 12, having secured thereto, by the holdfast devices 13, a vertical extending arcuate rack 14. The rack 14 has its upper portion bifurcated as at 15.

Mounted upon the supports 8—9 are transverse ties 16, having secured thereto a longitudinally extending platform 17, 70 which is of greater length than the length of the pit 6, and upon the upper face of said platform 17 extend the track rails 18—19. The former is provided with vertically disposed openings 20—21 which align with 75 openings 22 formed in certain of the ties 16. The rail 19 is provided with vertically disposed openings 23—24 which align with the openings 20—21, and which also align with vertical openings formed in the ties which 80 are provided with the openings 22.

Secured in the supports 8—9, and extended transversely of the pit 6, is a shaft 25 having eccentrically mounted thereon a shaft frame 26 which is arranged within and projects forwardly from the pit 6. The rear end of the frame 26 is provided with a weight 27, and the forward end with a trip bar 28, the latter being arranged in the path of a hoisting cage not shown. The weight 27 provides a counterbalance frame and is employed for normally maintaining the bar 28 elevated. As the frame 26 is eccentrically mounted, the normal position of said frame will be at an inclination with the weighted 95 end lowered, and by normally setting up the frame 26 in the manner as stated, a pair of vertically disposed stop members 29—30 are normally projected through the openings 21—24. The stop members 29—30 are 100 pivotally connected as at 31 to the sides of the frame 26, near the forward end thereof.

Pivotally connected to the sides of the frame 26, rearwardly with respect to the stop members 29—30, as at 32, are vertically disposed stop members 33—34 which extend through the openings 20—23. As the rear portion of the frame 26 is normally lowered, it is obvious that the stop members 33—34 will normally be in a lowered po- 110

2
sition. The length of the stop members 29—30 is such that when the frame is in normal position, the said stop members will project above the rails 18—19, and in the path of the forward wheels 35 of the car 36. The length of the stop members 33—34 is such, that when the frame 26 is in normal position, the upper ends of the said stop members will be positioned below the treads 10 of the rails 18—19 so as not to interfere with the travel of the car 36, as the same travels toward the stop members 29—30 to be arrested thereby.

When the bar 28 is depressed by the hoisting cage, when this latter descends to the bottom of the shaft 5, the frame 26 is lowered upon the shaft 25, whereby the forward end of said frame 26 will be lowered, carrying the stop members 29—30 therewith, and releasing the car 36 so that the latter can be loaded upon the hoisting cage. When the forward end of the frame 26 is lowered, the rear end thereof is elevated against the action of the weight 27, and as the rear end of said frame 26 is elevated, the stop members 33—34 are carried therewith whereby the upper ends of said stop members 33—34 will be projected above the treads of the rails 18—19, and in advance of a car in the rear of the car 36, so that the stop members 33—34 will engage the front wheels of said car and arrest movement thereof. When the hoisting cage ascends with a car thereon, the bar 28 is released, and the weight 27 comes into action, and will lower the rear end of the frame 26 and elevate the front end of said frame. As the front end of the frame 26 is raised, the stop members 33—34 are lowered, which releases the car, or as the stop members 33—34 are lowered, the stop members 29—30 are elevated, so that as the car moves forward, it will be arrested by the stop members 29—30.

To permit of the operation of the hoisting cage, without loading the cars thereon, and to arrest movement of the cars so that they cannot move on the hoisting cage, when the frame 26 is operated, a pair of

stop members 37—38 are provided, which are adapted to be projected upwardly 50 through openings 39—40 formed in the track rails 19—18, and in openings in the platform 17 which align with the openings 39—40. The stop members 37—38, are pivotally connected at their lower ends as at 41, 55 to crank arms 42, carried by a shaft 43, which is journaled in the members 8—9, and extends into the rack 14. The shaft 43 has fixed thereto as at 44, a lever arm 45 which extends up through the furcation of the 60 rack 14, and is provided with a spring pressed dog 46 adapted to engage in the rack 14 and maintain the shaft 43 in the position to which it has been shifted. The stop members 37—38 extend up through 65 the frame 26, and when the lever 45 is shifted rearwardly, the stop members are elevated so as to project in advance of the rear wheels 47 of the car 36, and will arrest movement of the car 36 toward the hoisting 70 cage, whether the frame 26 is shifted by the cage or by the weight 27.

What I claim is:—

In combination, a track leading to a hoisting cage shaft, a pit arranged below 75 said track, a normally inclined counter-balance frame pivotally supported in said pit and having its forward end projecting into said shaft and capable of being shifted by the descent of said cage, front and rear 80 stop elements pivotally connected to said frame and capable, when the latter is shifted, of being alternately retracted and projected into the path of travel of cars to release and arrest travel of the cars toward 85 said cage, and vertically movable stops, manually operated, and independent of both the hoisting cage and said first named stop elements, and located intermediate the front and rear stop elements first named. 90

In testimony whereof I affix my signature in the presence of two witnesses.

FERDINAND DAVIS.
